UNITED STATES PATENT OFFICE.

FREDERICK W. TUERK, JR., OF SYRACUSE, NEW YORK, ASSIGNOR OF TWO-THIRDS TO JAMES C. HUNTER, OF SAME PLACE, AND JOHN HUNTER, OF STERLING VALLEY, NEW YORK.

FAN.

SPECIFICATION forming part of Letters Patent No. 423,839, dated March 18, 1890.

Application filed November 2, 1889. Serial No. 329,006. (No model.)

To all whom it may concern:

Be it known that I, FREDERICK W. TUERK, Jr., of Syracuse, in the county of Onondaga, in the State of New York, have invented new and useful Improvements in Fans, of which the following, taken in connection with the accompanying drawings, is a full, clear, and exact description.

My invention relates to an improvement in fans, and has for its object the production of a simple and effective device whereby the blades or vanes of the fans are readily turned so as to displace more or less air or to throw the same upward or downward, as desired.

My invention consists in the detail construction and arrangement of the parts, all as hereinafter more particularly described, and pointed out in the claims.

In describing this invention reference is had to the accompanying drawings, forming a part of the specification, in which like letters indicate corresponding parts in all the views.

Figure 1 is an elevation representing a pendent fan of my improved construction, the supporting-bracket for the fan-blades being shown somewhat in perspective. Fig. 2 represents an enlarged elevation taken at right angles to Fig. 1, and illustrating particularly the supporting-bracket and the relative arrangement of my improved mechanism for axially rotating the fan-blades. Fig. 3 represents an enlarged view, partly in section, of the parts as illustrated in Fig. 2; and Fig. 4 represents a horizontal sectional view taken on line xx , Fig. 2, further illustrating the arrangement and construction of the parts shown in said figure.

This invention relates to the same class of fans illustrated and described in my pending application, Serial No. 302,396, and it sets forth particularly a different means for axially rotating the fan-blades, whereby the angle thereof may be varied at will and the agitation of the air increased or decreased by said variation without adjustment of the speed of rotation of the fan.

A represents a bracket, which supports the shaft B for rotating the fan, and is pendent from the ceiling C, or other suitable support.

This bracket A may be of any desired form and construction, and is here illustrated as provided with an upper journal a and a lower journal a' , between which on the shaft B is secured a suitable wheel or pulley B', to which power is transmitted by any desired belting or other transmitting mechanism.

Secured at the lower extremity of the shaft B is the supporting-frame D for the fan-blades F. This frame D, as best illustrated in Figs. 2, 3, and 4, is composed of the central or main portion D', preferably of greater width at its central part than at the top and bottom, and provided with the upper hub d , in which is secured the lower extremity of the shaft B, and the lower hub d' , in which is guided the mechanism for axially revolving the fan-blades. The fan-blades F are arranged on either side of said central portion D' and on either side of its center, so that a space intervenes between their adjacent extremities.

As illustrated, the fan-blades consist of the operating or body portion f , which is preferably formed of wood, paper, or other light material, and the shank f' secured by a set-screw f^2 , or other suitable device, to a spindle G, journaled in bearings D², provided on the opposite sides of the frame D. Extending from the bearings D², on either side thereof, are the short bracing-arms D³ and the long bracing-arms D⁴, the latter being elevated upward, rounded downward, and then deflected inwardly and connected to the main body D'.

Formed or provided upon the inner extremities of the spindles G are suitably-shaped studs or projections g , which are illustrated as a short piece of wire passed through an opening in the inner ends of said spindles. These spindles are retained in position by means of the shank f'' of the fan-blade F, and the washer or sleeve g' interposed between the inner bearing-face of the journal-bearing D² and the stud g .

By reference to the drawings it will be readily perceived that the elevated bracing bar or portion D⁴ is arranged directly opposite to the bearing D² on the opposite side of the frame D, and by this construction of the parts I am enabled to first provide the spindle G with its projection or lug, and then force the

same to its desired position in the frame. If this arm were not elevated, it will be readily understood that I would necessarily be obliged to first force said spindle to its operative position and to then secure the projection *g* thereto.

Sliding within the frame *D*, and engaging the lugs or projections *g*, is the block or head *H*, which may also be of suitable form and 10 construction. The preferable manner of guiding said sliding block or head consists in providing the same with the depending rod *h*, guided in the lower hub *d'* of the frame *D*. At the upper extremity of said block *H* are 15 the projecting ears *H'*, in which are journaled the separate pins *I*, revoluble independently of each other. Provided in the adjacent extremities of said pins or studs are suitable openings, with which the projections or lugs 20 *g* are readily engaged. Loosely mounted upon the lower extremity of the depending-rod *h* is a sleeve *J*, (here shown as an ordinary oil-cup,) provided with an upwardly-extending hub *j*.

When the several parts of my invention 25 have been operatively assembled, and motion is communicated to the wheel *B'*, it will be readily understood that the rotation of the frame *D* will revolve the fan-blades *F*, and that the air will be thrown upward or downward and with a greater or less degree of force, according to the degree of altitude of said fan-blades.

When desired to adjust the fan-blades and the consequent force or direction of the agitated air, the sleeve or oil-cup *J* is engaged 35 by the hand, and when the shaft *B* is revolved in the direction indicated by the arrow said oil-cup is forced downward to throw the air downward, and upward to throw the air upward. This operation or axial rotation of the 40 fan-blades is a very essential feature, rendering the fan much more desirable and enabling the operator to readily adjust the degree of force or direction of the agitated air without 45 changing the actuating mechanism of the fan, which in most cases is an extremely difficult operation. It will readily be understood that to whatever position the fan-blades are adjusted the arrangement of the axially-rotating 50 mechanism is such that the strain upon the fan-blades is not exerted in a direction to change the adjusted position thereof.

In order to prevent an undue elevation of the sleeve *J* and a consequent disarrangement of the parts, the upwardly-projecting hub *j* contacts with the lower face of the hub *d'*, and thus acts as a stop for the upward movement of said sleeve.

The operation of my invention will be readily understood from the foregoing, and it will 60 be noticed that the parts are simple both in construction and operation, are readily assembled, and that the peculiar construction of the frame affords great rigidity and prevents springing of the spindles for the fan-blades, and is also neat and attractive in appearance, being both useful and ornamental. It will, however, be understood that the parts might be somewhat different from the described construction; hence I do not limit myself to their precise form and arrangement. 70

Having thus fully described my invention, what I claim as new, and desire to secure by Letters Patent, is—

1. In a fan, the combination of a supporting-frame, fan-blades mounted on opposite sides of said frame, a projection or lug secured to the adjacent extremities of said fan-blades, a sliding block or head, and independently-moving supports carried by said 80 head and engaged with said lugs for axially rotating the fan-blades, substantially as described. 75

2. In a fan, the combination of a supporting-frame, fan-blades mounted on opposite 85 sides of said frame, a projection or lug secured to the adjacent extremities of said fan-blades, a sliding block or head guided in said frame, independently-moving supports carried by said block for engaging said projections and rotating the fan-blades, a depending rod extending from said head or block, a loose sleeve mounted on said rod, and a shoulder for abutting against said supporting-frame, substantially as specified. 90

3. In a fan, the combination of a supporting-frame, fan-blades mounted on opposite sides of said frame, a projection or lug secured to the adjacent extremities of said fan-blades, a sliding block or head engaging a 100 guideway provided in said frame, upwardly-extending projections provided on said sliding block or head, and the pins or supports *H*, journaled in the separate projections of the sliding block or head and engaging the 105 projections or lugs upon the fan-blades, substantially as described. 95

In testimony whereof I have hereunto signed my name, in the presence of two attesting witnesses, at Syracuse, in the county of Onondaga, 110 in the State of New York, this 28th day of October, 1889.

FREDERICK W. TUERK, JR.
